TOWEL INDICATOR FOR TOWEL CABINETS

Joseph N. Borroughs, Oakland, Calif.

Application October 24, 1932, Serial No. 639,176

19 Claims. (Cl. 33—128)

This invention is a towel indicator for towel cabinets and is specially directed to an indicating device for indicating substantially the proportionate diameter of roll, or amount of unused towel remaining in the usual sanitary towel cabinet utilizing toweling in roll form.

It is the main object of this invention to provide an indicator which will indicate substantially the amount of unused toweling or proportionate diameter of roll remaining in the cabinet, so that proper provision may be made for the renewal of the roll in ample time before the last of the previous roll is used.

Another object of the invention is to provide such an indicator in a position most convenient for viewing, and to provide means for maintaining the relative position of the roll to the indicator as the diameter of the roll decreases.

Other objects and advantages of the invention will become apparent as the following description is read on the drawing forming a part of the specification, and in which similar reference characters are used to indicate similar parts throughout the several views, of which:

Fig. 1 is a fragmentary front elevation of a towel cabinet with my invention applied thereto;

Fig. 2 is a section taken on line 2—2 of Fig. 1;

Fig. 3 is a section similar to that of Fig. 2 except showing the indicator as applied to a partly used roll of toweling;

Fig. 4 is a front view of Fig. 3 with the indicating scale and front of the cabinet removed;

Fig. 5 is a section taken on line 5—5 of Fig. 2.

The invention is applicable to any type of towel cabinet employing toweling in roll form, the cabinet being fragmentarily indicated in the views, and consisting of a back 10, top 11, front or door 12, and sides 13. The towel feeding mechanism is not indicated in the drawing, as there is no cooperative relation between the specific type of feeding mechanism and the indicator. The towel cabinet also includes a rack or basket 14 in which the roll of toweling 15 is retained. The parts so far enumerated and described do not form a part of the invention, except in the combination therewith.

The invention consists of a member which gravitationally cooperates with the periphery of a roll of toweling, and consists preferably of a U shaped member having legs 16 and 17 and a connecting member 18 forming the transverse element of the U shaped member and also forming a pintle which cooperates with the pintle sleeves or cooperating hinge members 19, which

hinge members are secured to the inner surface of the back 10 of the cabinet.

Telescopically disposed on the leg 17, is a sleeve 20, the outer end of this sleeve having a ball or other enlarged end 21, forming an indicating pointer and coincidentally forming means for retaining the indicator consisting of the tubular member 20 and ball 21 secured to the door 12, so that when the door 12 is opened, the indicator is removed from the leg 17, permitting convenient replacement of the roll of toweling 15. As is noted, the tubular member 20 is separable from the leg 17 and due to this member being telescopic as related to the leg 17, the variation in distance from the hinge member 19 to the front of the cabinet is compensated for during the indicating travel of the member 21.

The means for maintaining the roll of toweling in relative position to the indicator 21 consists of a tubular member 25 which is fixedly connected 20 to the tubular member 20 by means of the cross rod 26, and has an integral depending leg 27 projecting diagonally rearward, and cooperates with the periphery of the roll, urging the roll forward as the diameter of the roll decreases and 25 the ball 21 drops downwardly in its slot, the roll of toweling peripherally cooperating through its decrease in diameter with substantially the same point on the member 25 whereby uniform indication is provided. Other means may be readily 30 provided, such as sloping the bottom of the basket to cause the roll to assume a certain position irrespective of its diameter.

The member 20 slidably operates through a slot 22 formed in the front of the cabinet, this slot 35 being preferably inwardly diverging to permit swinging motion of the member 20 while the door 12 is being opened, when a door is provided at this point, the outer edge of the slot being sufficiently narrow to cause retention of the ball 40 or enlarged end 21 of the member 20.

Secured to the front of the cabinet or door, is an indicating scale 23 which is provided with a viewing slot 24, through which the ball 21 is clearly visible, this viewing slot being sufficiently narrow 45 to prevent the ball 21 passing therethrough, whereby a housing is formed, which in cooperation with the cabinet forms a retaining member for the enlarged end or ball 21, but which will permit oscillatory movement of the ball 21 for indicating the remaining toweling or proportionate diameter of the roll 15.

It will be noted that the leg 16 cooperates with the periphery of the roll of toweling, when the member 25—27 is not provided, that the leg 17 is 55

slidable in the tubular member 20 and separable therefrom, that the transverse element 18 of the U member forms one element of the hinge or a pintle for cooperation with the eyes or sleeves 19, 5 that the indicating scale 23 coincidently forms a viewing element for the indicator and a retaining housing therefor, and that the member 20 is separable from the member 17 merely by swinging the door open when provided, and which requires 10 only aligning of the two devices or elements when the door is being closed to place the indicator in operation, and that the indicator in no way interferes with the insertion or replacement of a roll of toweling or with the opening of the door, 15 It will be noted also that this indicating element including the members 17 and 20 can be placed on the outside of the side wall 13 if so desired, or may be operable through a panel in the front of the cabinet and that many variations may be 20 made operating on the same principle.

Where the means 25-27 is provided, these elements cooperate with the roll and are separable from the leg 16 coincidently with the member 20 from leg 17.

25 It will also be noted that variations in construction and arrangement of parts which are consistent with the appended claims, may be resorted to without detracting from the spirit or scope of the invention, or sacrificing any of the advantages 30 thereof.

I claim:—

1. An indicator for a towel cabinet having a slot in the front thereof, comprising a member 35 gravitationally cooperating at one point with the periphery of a roll of toweling to indicate the proportionate diameter of the roll and at another point to retain cooperation at the one point during decrease in diameter of the roll, and having an indicating element operating through the 40 slot formed in the front of the cabinet, said member being of U form and having one leg cooperating with the roll and the other leg cooperating with the indicating element, the connecting portion forming a supporting element for the member.

2. An indicator for a towel cabinet having a slot in the front thereof, comprising a member 50 gravitationally cooperating with the periphery of a roll of toweling and having an indicating element operating through the slot formed in the front of the cabinet, and an indicating scale in cooperative relation to the indicating element, said member being of U form and having one leg 55 cooperating with the roll and the other leg cooperating with the indicating element, the connecting portion forming a supporting element for the member.

3. An indicator for a towel cabinet having a slot in the front thereof, comprising a member 60 gravitationally cooperating with the periphery of a roll of toweling and having an indicating element operating through the slot formed in the front of the cabinet, said member being hingedly mounted within the cabinet and of U form with 65 the cross member forming the pintle of the hinge joint, one of the legs cooperating with the periphery of the roll of toweling and the other leg cooperating with the indicating element.

70 4. An indicator for a towel cabinet having a slot in the front thereof, comprising a member 70 gravitationally cooperating with the periphery of a roll of toweling at two points, for indicating the proportionate diameter of the roll and urging the decreasing roll toward the front of the cabinet, and having an indicating element operating

through the slot formed in the front of the cabinet, said member being hingedly mounted within the cabinet and of U form with the cross member forming the pintle of the hinge joint, one of the legs cooperating with the periphery of the roll of toweling at the two points and the other leg cooperating with the indicating element. 5

5. An indicator for a towel cabinet having a slot in the front thereof, comprising a member 10 gravitationally cooperating with the periphery of a roll of toweling and having an indicating element operating through the slot formed in the front of the cabinet, said indicating element being telescopically disposed on the member and having means for maintaining the indicator in 15 predetermined relation to the front of the cabinet during the indicating travel thereof.

6. An indicator for a towel cabinet having a slot in the front thereof, comprising a member 20 gravitationally cooperating with the periphery of a roll of toweling and having an indicating element 25 operating through the slot formed in the front of the cabinet, said member being of U form and having one leg cooperating with the roll and the other leg cooperating with the indicating element, the connecting portion forming a supporting element for the member, said indicating element being telescopically disposed on the member and having means for maintaining the indicator in 30 predetermined relation to the front of the cabinet during the indicating travel thereof.

7. An indicator for a towel cabinet having a slot in the front thereof, comprising a member 35 gravitationally cooperating with the periphery of a roll of toweling and having an indicating element 40 operating through the slot formed in the front of the cabinet, and an indicating scale in cooperative relation to the indicating element, said indicating element being telescopically disposed on the member and having means for maintaining the indicator in 45 predetermined relation to the front of the cabinet during the indicating travel thereof, said means for maintaining the indicator in predetermined relation consisting of an enlargement on the indicator forming a pointer, said indicating scale coincidently forming a retaining housing for the pointer and having a viewing slot for the pointer formed in the front thereof.

8. An indicator for a towel cabinet having a slot 50 in the front thereof, comprising a member gravitationally cooperating with the periphery of a roll of toweling and having an indicating element operating through the slot formed in the front of the cabinet, said member being of U form and having one leg cooperating with the roll and the other leg 55 cooperating with the indicating element, the connecting portion forming a supporting element for the member, said indicating element being telescopically disposed on the member and having means for maintaining the indicator in predetermined relation to the front of the cabinet during the indicating travel thereof, said means for maintaining the indicator in predetermined relation consisting of an enlargement on the indicator forming a pointer, said indicating scale coincidently forming a retaining housing for the pointer and having a viewing slot for the pointer formed in the front thereof. 60

9. An indicator for a towel cabinet having a slot 70 in the front thereof, comprising a member 70 gravitationally cooperating with the periphery of a roll of toweling and having an indicating element operating through the slot formed in the front of the cabinet, said member being hingedly

taining housing for the pointer and having a viewing slot for the pointer formed in the front thereof, said indicating element being separable from the member when the front of the cabinet is opened, to permit opening of the front of the cabinet and the insertion of a roll of toweling.

18. An indicator for a towel cabinet having a slot in the front thereof, consisting of a U-shaped member hingedly secured to the rear wall of the cabinet and having a leg thereof extending forwardly and supported upon a roll of towels in said cabinet, another leg of said member extend-

ing forwardly and protruding through said slot.

19. An indicator for a towel cabinet having a slot in the front thereof, consisting of a U-shaped member hingedly secured to the rear wall of the cabinet and having a leg thereof extending forwardly and supported upon a roll of towels in said cabinet another leg of said member extending forwardly substantially in parallel with said first named leg, and a telescopically connected extension to said last named leg and protruding into 10 said slot.

JOSEPH N. BORROUGHS.
